UNITED STATES PATENT OFFICE.

CHARLES P. HOLMES, OF LYNN, MASSACHUSETTS, ASSIGNOR TO UNITED SHOE MACHINERY COMPANY, OF PATERSON, NEW JERSEY, A CORPORATION OF NEW JERSEY.

WELT-SEWING MACHINE.

1,071,050.

Specification of Letters Patent. Patented Aug. 26, 1913.

Application filed August 30, 1909. Serial No. 515,157.

To all whom it may concern:

Be it known that I, CHARLES P. HOLMES, a citizen of the United States, residing at Lynn, in the county of Essex and State of Massachusetts, have invented certain new and useful Improvements in Welt-Sewing Machines; and I do hereby declare the following to be a full, clear, and exact description of the invention, such as will enable others skilled in the art to which is appertains to make and use the same.

The present invention relates to welt sewing machines adapted for use in sewing the welt to the insole and upper of a shoe and more especially to devices for drawing the welt back through the welt guide after it has been severed from the shoe so that its end will be in proper position for attachment to the succeeding shoe at the beginning of the sewing operation.

In removing a shoe from a welt sewing machine after the sewing operation has been completed, the operator draws a sufficient length of welt through the welt guide to enable him to conveniently sever the welt from the shoe. This leaves a considerable length of welt projecting beyond the welt guide which should be drawn back through the welt guide in order to bring the end of the welt into proper position for attachment to the succeeding shoe. The drawing back of the welt to the proper extent requires care and attention on the part of the operator with a resulting loss of time and reduction in the production of the machine. It has been proposed to provide devices for drawing back the welt after it has been severed from the shoe, but these devices have not proved satisfactory principally for the reason that they have been constructed to draw back a uniform length of welt regardless of variations in the length of welt drawn through the guide by the operator in removing the shoe from the machine.

It is accordingly the object of the present invention to provide a mechanism for retracting the welt which will operate to draw the proper length of welt back through the welt guide without requiring special care or attention on the part of the operator and to otherwise improve the construction and mode of operation of welt retracting devices.

To these ends one feature of the inven-

tion contemplates the provision of welt retracting means for drawing a length of welt back through the welt guide which varies in accordance with the length drawn forward through the guide in removing the shoe. By this means the welt is drawn back through the guide to bring its free end into proper position for attachment to the shoe without regard to the length of welt drawn through the guide in removing the shoe. Broadly considered it is not material to this feature of the invention whether the operation of the welt retracting mechanism is automatic or requires more or less manual manipulation on the part of the operator.

A further feature of the invention contemplates the provision in a welt sewing machine of means which acts automatically to draw the welt back through the welt guide when the welt is severed from the shoe. In its broader aspects this feature of the invention contemplates the employment of any welt retracting means which is constructed and arranged to thus automatically retract the welt.

In its preferred form, the welt retracting means comprises a device which operates or is operated to grip the welt previous to the removal of the shoe by the operator, then moves forward with the welt as the shoe is removed and then returns to draw the surplus welt back through the welt guide when the welt is severed from the shoe. This construction and arrangement of welt retracting means constitutes a further feature of the invention and it is immaterial to this feature of the invention whether the welt gripping device is operated to grip the welt by the manipulation of the machine in removing the work or is otherwise operated to grip the welt. It is preferred, however, to provide means for operating the welt gripping device to grip the welt which is automatically thrown into operation or rendered active in bringing the parts of the machine into position for the removal of the completed shoe, since when thus operated the welt retracting mechanism does not require any special attention or manipulation on the part of the operator. This operation of the welt gripping device may be conveniently provided for by controlling or operating the welt gripping device from the

lever which operates to throw off the thread tension preparatory to the removal of a shoe.

In order that the end of the welt may project through the welt guide to the proper extent after the welt has been retracted, it is desirable that the return movement of the welt retracting device, after it has been drawn forward with the welt, should be somewhat less than its forward movement.

A further feature of the invention accordingly contemplates the provision, in a welt retracting mechanism provided with a welt engaging device which is movable with the welt during the removal of the shoe and which during its return movement draws the welt back through the welt guide, of means for releasing the welt before the device has completed its return movement. Any suitable means may be employed for thus releasing the welt and it is not material to this feature of the invention, in its broader aspects, whether the return of the welt retracting device or the release of the welt is automatically effected or not. In its preferred form this feature of the invention contemplates the provision of a stop for arresting the welt engaging device before it has reached its initial position and the automatic release of the welt and return of the device to its initial position upon the starting of the machine.

In addition to the above features the invention includes certain further features of construction and arrangement referred to in the claims which contribute to the sufficiency and simplicity of the mechanism.

The various features of the invention will be readily understood from the accompanying drawings and the following detailed description of the construction shown and referred to therein.

In the drawings Figure 1 is a front elevation of a welt sewing machine provided with the present invention in its preferred form; Fig. 2 is a side elevation of the machine; Fig. 3 is a detailed plan view of the welt retracting mechanism; Fig. 4 is a horizontal sectional view on line 4-4, Fig. 5; Fig. 5 is a front elevation of the part shown in Fig. 3; and Fig. 6 is a side elevation looking toward the left in Fig. 5.

As shown in the drawings, the invention is illustrated as embodied in the well known Goodyear welt and turn sewing machine, which is disclosed in the patent to French and Meyer, No. 412,704, Oct. 8, 1889. It is to be understood, however, that the invention is not limited in this application to this form of machine but may be embodied in or applied to various forms or types of welt sewing machines.

In the machine illustrated 1 indicates the needle, 2 the feed point, 3 the channel guide, 4 the looper, 5 the take-up, 6 the welt guide

and 7 the back rest, these parts being constructed and operated in the manner set forth in the patent above referred to. The machine is also provided with the usual tension device 8 and tension controlling lever 9 which is operated through a bell crank lever 10, rod 11, and cam 12, by turning back the cam shaft of the machine at the completion of the sewing operation in the usual manner. In addition to these devices, the machine is also provided with the welt retracting mechanism embodying the various features of the present invention in their preferred form. In the construction of this mechanism shown, the means for retracting the welt comprises a device for engaging and gripping the welt consisting of a fixed welt gripping jaw 13 and a movable welt gripping jaw 14. The jaw 13 is formed at the upper end of an arm 15 which is pivoted at 16 to a bracket 17 so that it may swing in the direction of the travel of the welt. The jaw 14 is formed by the upper end of a lever 18 which is pivoted at 19 on the arm 15 so that it may move toward and from the jaw 13 to grip and release the welt which passes between the jaws. The jaw 13 is pressed normally in a direction to release the welt by a spring 20. The welt is guided and retained between the welt gripping jaws by an over-hanging flange 21 on the upper end of the arm 15 and a pin 22 which may be secured in any one of a series of holes in the arm 15 in accordance with the width of welt which is being used. The jaw 13 is preferably provided with corrugations or teeth for preventing relative movement between the welt and gripping jaws when the jaws are operated to grip the welt. The welt gripping jaws are held normally in retracted position by a spring 23.

During the operation of the machine the welt gripping jaws are disengaged from the welt and the welt passes freely between the jaws and through the welt guide. When the sewing of the shoe is completed, the operator turns the cam shaft back to bring the stitch forming devices into proper position for the removal of the shoe and this backward movement of the cam shaft operates the lever 9 to relieve the tension on the thread. This movement of the lever 9 also brings a cam plate 24 which is secured to the lever against a pin 25 projecting from the lower end of a bell crank lever 26, the upper end of which carries a roll 27 engaging the lower end of the gripping lever 18. The cam 24 acting through these connections operates the lever 18 to engage the welt gripping jaws with the welt. Now when the operator removes the shoe and draws forward the welt through the welt guide, the welt gripping jaws move forward with the welt against the tension of the spring 23, the lower end of the arm 18 being so

shaped that it remains in engagement with the roll 27 during this movement of the welt gripping jaws. When the operator severs the welt from the shoe, the spring 23 acts to return the welt gripping jaws toward their initial position and thus draw the welt back through the welt guide.

In order that the proper length of welt may be left projecting through the welt guide, the welt gripping jaws are operated to release the welt before they reach their initial position. In the construction shown, the return movement of the welt gripping jaws is arrested by a stop 28 which is so arranged that it does not interfere with the forward movement of the welt gripping jaws but extends into the path of a lug 29 on the arm 15 during the return of the welt gripping jaws and arrests their return movement. As shown, the stop 28 is in the form of an arm pivoted on one arm of a bell crank lever 30 and held yieldingly against a stop shoulder 31 on the lever by a spring 32. The lever 30 is held normally in position to support the arm 28 in the path of the lug 29 on the arm 15 by a spring 33, Fig. 2. When the welt gripping jaws are advanced with the welt, the spring 32 yields to allow the passage of the arm 15 and immediately returns the arm 29 into normal position against the stop 31 after the arm 15 has passed. On the return movement of the arm 15, therefore, the lug 29 strikes against the end of the arm 28, thus arresting the welt engaging grippers before they have completed their return movement. The welt gripping jaws, therefore, act to draw back through the welt guide a length of welt which is less than the length drawn forward through the guide by an amount depending upon the position of the stop arm 28 with relation to the initial position of the welt gripping jaws. By properly arranging or adjusting the stop arm 28, therefore, a proper length of welt will be left projecting beyond the welt guide without regard to the length of welt which is drawn forward through the guide by the operator in removing the shoe.

When the machine is started, the tension controlling lever 9 is operated to put on the tension and this movement of the lever 9 releases the lever 26 so that the welt gripping jaws are open to release the welt. During the first revolution of the cam shaft, a cam 34, carried by the cam shaft of the machine, actuates the lever 30 to swing the stop arm 28 out of engagement with the lug 29, as indicated in Fig. 5, so that the welt gripping jaws return to their initial position.

While it is preferred to employ the construction and arrangement of parts shown and described, it will be understood that this construction and arrangement is not essential, except so far as it is specified in the

claims, and may be varied and modified as found desirable or to suit the construction and arrangement of the parts of the machine in which the invention may be embodied without departing from the broader features of the invention. It will also be understood that certain features of the invention are not limited in their application to mechanism which retracts the welt drawn forward through the welt guide, but may be embodied with advantage in other forms of mechanism for controlling the movement of the welt at the completion of the sewing operation, or between successive sewing operations.

Having explained the nature and object of the invention and one form of mechanism in which it may be embodied, what I claim is:

1. A sewing machine, having, in combination, stitch forming mechanism, a welt guide, and means acting automatically to draw the welt back through the guide after it is severed from the shoe, substantially as described.

2. A sewing machine, having, in combination, stitch forming mechanism, a welt guide, and means acting automatically to draw back through the guide less welt than is drawn forward through the guide in removing the shoe, substantially as described.

3. A sewing machine, having, in combination, stitch forming mechanism, a welt guide, a welt retractor, and means for imparting to said retractor a welt drawing movement less by a uniform predetermined amount than the length of the welt drawn forward through the guide, substantially as described.

4. A sewing machine, having, in combination, stitch forming mechanism, a welt guide, a device for gripping the welt previous to the withdrawal of the shoe movable with the welt, means for returning the device to draw the welt back through the guide after it is severed from the shoe, and means for releasing the welt before the device has completed its return movement, substantially as described.

5. A sewing machine, having, in combination, stitch forming mechanism, a welt guide, a welt retractor constructed to grip the welt and move forward therewith as the shoe is withdrawn, means for returning the retractor to draw back the welt through the guide, and means for arresting the return of the retractor before it completes its return movement, substantially as described.

6. A sewing machine, having, in combination, stitch forming mechanism, a welt guide, a welt retractor constructed to grip the welt and move forward therewith during the removal of the shoe, means for returning the retractor to draw back the welt through the guide after it is severed from

the shoe, means for arresting the retractor before it has completed its return movement, and means for releasing the welt and completing the return of the retractor, substantially as described.

7. A sewing machine, having, in combination, stitch forming mechanism, a welt guide, a welt gripping device movable with the welt during the removal of the shoe, and a spring for holding said device in retracted position, substantially as described.

8. A sewing machine, having, in combination, stitch forming mechanism, a welt guide, a welt gripping device movable with the welt during the removal of the shoe, a spring for holding said device in retracted position, and a stop for arresting said device before it completes its return movement and means for thereafter rendering 20 the stop inactive, substantially as described.

9. A sewing machine, having, in combination, stitch forming mechanism, a welt guide, welt retracting mechanism, and means for engaging said welt retracting mechanism with the welt in bringing the sewing mechanism into position for the removal of the shoe, substantially as described.

10. A sewing machine, having, in combination, stitch forming mechanism including a tension device, a welt guide, means for relieving the tension at the completion of the sewing operation, a welt retracting mechanism including a welt gripping device, and connections for operating said device to grip the welt upon the release of the tension, substantially as described.

11. A sewing machine, having, in combination, stitch forming mechanism, a welt guide, a welt gripping device movable with the welt, means for retracting the welt gripping device to draw the welt back through the guide when it is severed from the shoe, means for arresting the welt gripping device before it has completed its return movement, and mechanism for releasing the welt and completing the return of said device upon the starting of the machine, substantially as described.

12. A sewing machine, having, in combination, stitch forming mechanism, a welt retracting device mounted to move with the welt as the welt is drawn forward, means

for actuating the device to grip the welt before the shoe is withdrawn, and means for returning the device to draw back the surplus welt when the welt has been severed, substantially as described.

13. A sewing machine, having, in combination, stitch forming mechanism, a welt retracting device mounted to move with the 60 welt, means rendered active in bringing the stitch forming mechanism into position for removal of the shoe for actuating the device to grip the welt, and means for returning the device to draw back the surplus welt 65 when the welt has been severed, substantially as described.

14. A sewing machine, having, in combination, a welt guide, a device for controlling the welt mounted to travel forward with the 70 welt as it is drawn forward through the guide, means for returning the device to normal position, and means for connecting the device with the welt previous to the withdrawal of the shoe, substantially as described.

15. A sewing machine, having, in combination, a welt guide, a welt controlling device movable with the welt as it is drawn forward, and means for connecting the device with the welt in bringing the machine 80 into position for the removal of the shoe, substantially as described.

16. A sewing machine, having, in combination, a welt guide, a device for gripping 85 the welt previous to the withdrawal of the shoe movable with the welt as it is drawn forward through the welt guide, a stop for determining the position of the gripper while gripping the welt, and means for freeing the gripper and returning it to initial position, substantially as described.

17. A sewing machine, having, in combination, stitch forming mechanism, a welt gripping device movable with the welt, 95 means for actuating the gripper to grip the welt in bringing the sewing mechanism into position for removal of the shoe, and means for actuating the gripper to free the welt, substantially as described.

CHARLES P. HOLMES.
